Primary Examiner — Sandra S Snapp*Assistant Examiner* — leisha N Price(74) *Attorney, Agent, or Firm* — Leason Ellis LLP(57) **CLAIM**

We claim the ornamental design for a lopper, as shown and described.

DESCRIPTION

FIG. 1 is a top perspective view of an embodiment of the claimed design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the tool handle and form no part of the claimed design.
